SWAGING DIE WITH AUTOMATIC SET

Felix R. Newell, Detroit, Mich.

Application October 12, 1942, Serial No. 461,691

9 Claims. (Cl. 76—95)

The present invention relates to improvements in forging dies and more particularly to a die for swaging the ends of drill bits and other boring tools.

The primary object of the invention, is to provide a swaging and forging die capable of being used for sharpening the cutting edges of drill bits and boring tools at the location of the boring operation without necessitating the boring tool being out of use for lengthy intervals of time during sharpening or swaging.

Another object of the invention is to provide a swaging die for sharpening the ends of drill bits and other boring tools which is compact and complete in its entirety whereby the boring tool may be inserted therein after being heated and forged to shape the end of the drill with renewed cutting teeth or surfaces.

Another object of the invention, is to provide a swaging die which is adapted to receive drill bits and other boring tools of various sizes without requiring complicated mechanical changes or the use of a different die member.

Another object of the invention is to provide a swaging die as set forth in the above mentioned objects having radially movable and adjustable die members capable of being adjusted by the insertion of holding blocks of various sizes which may be interchangeably used to position the radially movable die members so as to accommodate drill bits of various shapes and diameters.

Another object of the invention, is to provide a swaging die having radially adjustable die members which are of a predetermined size so that the outer ends will register with graduated markings formed on the base member to insure the proper positioning of the die members for a certain size drill bit.

Another object of the invention is to provide a clamping ring for securely holding the radially movable die members in position after they have been adjusted to accommodate a drill bit of a certain size, thereby eliminating the use of a series of fixtures and other holding members as has heretofore been used.

Other objects and advantages of the invention will become apparent during the course of the following description of the accompanying drawing wherein:

Figure 1 is a top plan view of the swaging die embodying the invention showing the parts in their assembled relation.

Figure 2 is a transverse cross sectional view taken on line 2—2 of Figure 1 looking in the

direction of the arrows and showing in detail the structural arrangement of the swaging die set.

Figure 3 is a cross sectional view taken on the zig-zag line 3—3 of Figure 1 looking in the direction of the arrows further illustrating details of construction.

Figure 4 is a cross sectional view taken on line 4—4 of Figure 1 looking in the direction of the arrows illustrating one of the adjusting blocks positioned in back of a radially movable die member.

Figure 5 is a perspective view of one of the adjustable die members showing the configuration thereof.

Figure 6 is a transverse cross sectional view similar to Figure 2 illustrating a drill bit in position for swaging and the manner in which the adjustable die members are located.

Figure 7 is a side elevational view showing a portion of a drill bit and illustrating the shape of the cutting teeth thereof.

Figure 8 is a bottom plan view of the drill bit shown in Figure 7 illustrating the cutting teeth or surfaces on the end thereof, and

Figure 9 is a side elevational view of the swaging die showing the same in position on the lower end of a drill during swaging operation.

In the drawing, wherein for the purpose of illustrating the invention and wherein like reference characters will be employed to designate like parts throughout the same, the reference character 5 will generally be employed to designate a base formed of a block of metal of polygonal shape and said base includes a bottom wall 6 and a top wall 7 which are substantially flat so that the bottom wall 6 may rest upon a suitable support during the swaging operation.

Formed in the top wall 7 is a cruciform groove including radially extending portions 8 formed by converging side walls 9 as shown in Figures 3 and 4. The converging walls 9 intersect as at 10 as is clearly shown in Figure 1.

Slidably received in each of the V-shaped grooves 8 is an adjustable die member 11 as shown in Figure 5 and the die members are formed of a block of metal having converging walls 12 forming a V-shaped block complementary with the V-shaped groove 9 so as to freely slide therein during adjustment. The inner wall 13 of each adjustable die member 11 is undercut as at 14 and extends upwardly as at 15 to a rounded portion 16, thereby providing a nose for engaging the portion of the drill bit above the cutting teeth. The top wall 7 of the block

5 is provided with a series of graduation marks

16 adjacent the V-shaped grooves 8 so that the opposite or outer wall will align therewith to indicate the position of the inner ends of the adjustable die members 11. In this manner, the adjustable die members 11 may be moved inwardly or outwardly so that the outer edge of each die block is in alignment with a predetermined graduation or marking 16.

The V-shaped grooves 8 terminate a slight distance short of the edge wall of the block 5 in a vertical wall 17 which is adapted to form an abutting wall for a series of interchangeable blocks 18 of various widths. Each of the blocks 18 is provided with a laterally extending arm 18^a having an aperture for being received on a hinge pin 18^b the ends of which are supported by upstanding lugs 18^c formed integral with the top wall 5. It is intended to provide a set of interchangeable graduated blocks 18 of different thickness in sets of four, so that the adjustable die members 11 may be set to a position determined by the thickness or size of the blocks 18. The blocks 18 are provided with converging lower walls 19 which engage the converging walls 9 of the groove 8 so that the major portion of each of the blocks 18 will abut the ends of the adjustable die members 11. By merely swinging the blocks 18 on their hinge connections 18^b into and out of the grooves 9, the die members may be set to any desired position.

A clamping ring 20 is adapted to be fastened to the block 5 by means of bolts 21 extending through openings therein as at 22 so that the lower threaded ends of the bolts will be received in threaded openings 23 formed in the block are radially spaced intervals. The upper ends of the bolts 21 are provided with heads 24 to facilitate the tightening or loosening of the bolts during the adjusting of the die members 11. Interposed between the clamping ring 20 and the top wall 7 are spacing bushings 25 having apertures 26 for receiving the bolts 21 and it is to be noted that the bolts 21 are spaced intermediate the radial grooves 8 to position the ring 20 centrally of the block 5. The clamping ring 20 is adapted to engage the upper surfaces of the adjustable die members 11 to prevent the vertical movement thereof during the swaging operation. Formed integral with the base 5 and extending laterally from opposite side walls thereon are outwardly directed lugs 30 to which is pivotally fastened as at 31, an upwardly swinging arm 32 having formed on the upper end thereof, a semicircular collar 33 adapted to encircle the drill D. Clamping bolts 34 extend through ears 35 for securely holding the base 5 on the end of the drill D.

In use, the drill D is first heated to a forging temperature and the hinged blocks 18 are swung on their hinge pintles to allow the die member 11 to be moved radially as far as possible. The end of the drill D is then inserted so that the teeth T are in registry with the grooves 8, as is shown in Figures 2 and 6. After the drill D has thus been positioned, the hinged arms 32 are swung upwardly so that the clamping portion 33 will encircle the drill D about the cutting end. The bolts 34 are now drawn tightly in place by means of a suitable wrench to frictionally clamp the sections 33 in place.

Having thus fastened the device in place, the die members are moved inwardly to a predetermined position so that one or all of the hinged graduated blocks 18 may be swung to a position in back of the die members to retain them in their adjusted position. To insure centering of

the drill D, the round nose portions 14 and 15 of the die members 11 will engage the vertical wall of the drill thereby preventing lateral movement of the drill during swaging. Simultaneously, the beveled surface 13 of the die members 11 will engage the outer end portions of the drill teeth T as at T' so that a definite shape will be imparted to both cutting edges. The drill and swaging die may now be suspended from suitable well rigging equipment and jarred by imparting sudden up and down movement thereto so that the end of the drill will assume the same profile characteristics as the grooves 8 and beveled end portions 13 of the die members 11.

If desired, the die set may be used for forming the teeth on new drills by simply inserting a bar of stock having one end heated to a forging temperature so that the metal will flow into conformity with the V-shaped grooves 8 and undercut beveled edge 13 when a series of blows are struck on the upper end of the bar stock by a relatively heavy hammer.

It is to be understood that the form of the invention herewith shown and described is to be taken as a preferred embodiment of the same, and that various changes in the shape, size and arrangement of parts may be resorted to without departing from the spirit of the invention or the scope of the subjoined claims.

What I claim is:

1. A swaging die, comprising a base having a cruciform groove in its top wall, die members radially movable in the groove, interchangeable blocks for setting the die members in a predetermined position and a circular retaining member engaging the die members for anchoring the die members in an adjusted position.

2. A swaging die, comprising a base having a cruciform groove formed in the top wall adapted to conform to the cutting edge of a drill bit, a series of die members movably mounted in the extension of said groove, interchangeable blocks positioned between the ends of the die members and the outer ends of the groove extensions and a retaining member for anchoring the die members in an adjusted position.

3. A swaging die, comprising a base having a cruciform groove of V-shaped cross section adapted to shape and configure the cutting end of a drill bit, radially movable die members in the arms of said groove, interchangeable adjusting blocks for said die members and a circular retaining member for anchoring said die members in a predetermined adjusted position.

4. A swaging die, comprising a base having a cruciform groove of V-shaped formation in its top wall, the intersecting portion of said groove being adapted to configure and shape the cutting end of a drill bit when presented thereto in a heated condition, radially movable cooperating die members adjustably mounted in the groove and interchangeable size blocks interposed between the end walls of the groove and said die members for holding the die members in an adjusted position.

5. A swaging die, comprising a base having a cruciform groove of V-shaped cross section adapted to receive and shape a cutting tool when presented to the intersecting portion of said cruciform groove, cooperating die members radially movable in the cruciform groove, interchangeable adjusting blocks mounted in back of the die members and a retaining member for holding the die members in an adjusted position.

6. A swaging die, comprising a base having a

drill bit engaging surface to impart a definite contour to the drill bit end, cooperating die members carried by the base having beveled surfaces for imparting a profile to the edges of said drill bit and interchangeable adjusting blocks positioned in back of the cooperating die member to hold the die member in an adjusted position.

7. A swaging die, comprising a base having surfaces adapted to be engaged by a drill bit when heated to a forging temperature to shape and configure said drill bit surfaces to form cutting edges, cooperating die members carried by the base for engaging the outer edges of the drill bit cutting surface, said die members having undercut ends for allowing the metal on the cutting edges of a drill bit to flow therebeneath, size blocks interchangeably positioned between the outer ends of said die member and said base and a retaining ring engaging the upper surfaces of said die members for securing the die members in an adjusted position.

8. A swaging die, comprising a base having a drill bit engaging surface for imparting a defi-

nite shape to the end of the drill bit, movable cooperating die members carried by the base adapted to provide a drill bit edge forming surface, interchangeable adjusting blocks for retaining the die members in a preset position and a retaining ring clampingly engaging the top wall of the cooperating die members.

9. A swaging die, comprising a base having a cruciform recess defining radially extending grooves in the top wall thereof providing a cutting tooth shaping portion for drill bits, said grooves being V-shaped in cross-section to impart a definite shape to the cutting teeth, cooperating die members movably mounted in said grooves having beveled inner ends for imparting a definite shape to the outer edges of the drill bit cutting teeth, interchangeable blocks mounted in the ends of the V-shaped grooves for adjusting the die members, and a retaining ring clampingly engaging the top surface of the die members.
